Primary Examiner — Patricia A Palasik(74) *Attorney, Agent, or Firm* — Morgan, Lewis & Bockius LLP(57) **CLAIM**

The ornamental design for a laser resonator, substantially as shown and described.

DESCRIPTION

FIG. 1 is a perspective view of a laser resonator incorporating the design;

FIG. 2 is a front view thereof;

FIG. 3 is a back view thereof;

FIG. 4 is a left-side elevation view thereof;

FIG. 5 is a right-side elevation view thereof;

FIG. 6 is a top view thereof; and,

FIG. 7 is a bottom view thereof.

The broken lines in the drawings depict portions of the laser resonator that form no part of the claimed design.
